UNITED STATES PATENT OFFICE.

NATHANIEL G. PARRY, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed September 6, 1921. Serial No. 498,872.

This invention comprehends improvements of general utility in the coking retort oven art; and also comprehends certain improvements especially applicable to coking retort ovens of the well-known cross regenerative type exemplified in the patent to H. Koppers No. 818,033, dated April 17, 1906, and in the patent to Joseph Becker No. 1,374,546, dated April 12, 1921.

The invention has for objects the provision of a coking retort oven having, as important characteristics: a flue construction that contemplates the entire elimination of the usual horizontal or bus flues that are located at the top of the vertical flame flues and connect a plurality of said vertical flues with each other; and, as a feature that may be secured by the above structural improvements, a novel system of control of the flow through the flame flues of the heating walls, permitting flow in the same direction through all the flame flues of each heating wall, with the result that all the flame flues of each heating wall are either simultaneously burning, or simultaneously operating as out-flow flues for carrying away the waste gases to outflow operating regenerators.

The above stated elimination of the horizontal flues is an important advantage for the reason that it enables a considerable thickening and strengthening of the walls of the oven structure in the region located at the upper extremity of the vertical flame flues. Moreover, the improved construction of the invention permits an increase of the height of the flame flues, with a corresponding increase in the height of the coking chambers, so that the latter may be made narrower in width, a development greatly facilitating the coking of high volatile coals, yet having adequate provision for taking care of the increased volume of combustion products, without making it necessary to provide flue spaces of sizes inconsistent with adequate strength of the wall construction. The flue construction of the invention is furthermore of great importance in oven batteries fired with extraneously derived gas, such as producer gas, since the employment of such gas results in an increased volume of combustion products and adequate flue spaces must be provided to collect and feed to the down-flow operating flues this increased volume of combustion products. By the invention, the flue construction may be

adequately accommodated to such increased volume of combustion products, without introducing elements of weakness into the wall structure.

In addition to the objects recited above, 60 the invention comprehends a novel regenerator construction and system of flow therethrough and through the flues, promoting uniformity of distribution, and has for other objects such other improvements and advantages in construction and operation as are found to obtain in the structures and devices hereinafter described or claimed.

In the accompanying drawings, forming a part of this specification, and showing, for 70 purposes of exemplification, a preferred form and manner in which the invention may be embodied and practiced, but without limiting the claimed invention to such illustrative instance or instances:

Figure 1 is a composite crosswise vertical section through a coke oven battery embodying features above specified and equipped with the improvements of the invention, the view being taken longitudinally through a 80 heating wall and a pair of regenerators in planes indicated by the lines D—D and E—E of Fig. 2;

Fig. 2 is a composite vertical sectional elevation taken longitudinally of the coke oven battery, in planes indicated by the lines A—A, B—B and C—C of Fig. 1; and

Fig. 3 is a composite horizontal section taken in planes indicated by the lines G—G, H—H and K—K of Fig. 2.

The same characters of reference designate the same parts in each of the several views of the drawings.

In the embodiment illustrated in the drawings, the invention is incorporated in a combination coking oven battery, i. e., a battery having provision for being operated either with producer gas as the fuel or with coke oven gas burned in an atmosphere of ordinary preheated air, such as is utilized in an ordinary coke oven, or with coke oven gas burned in an atmosphere containing both air and a neutral gaseous diluent which is introduced into the flame flues separately from the air. A combination coke oven battery having such features is described and claimed in the co-pending application of Joseph Becker for Letters Patent of the United States for a coking retort oven, filed April 23, 1920, Serial No. 376,126. For con-

venience, the present description will be confined to the present illustrative embodiment of the invention in such a combination oven battery; the novel features and improvements of the invention are, however, capable of other applications, such for example, to ordinary so-called "coke ovens" employing coke oven gas as the fuel, or to ordinary so-called "gas ovens" employing an extraneously derived gas, such as producer gas, as the fuel; hence the scope of the invention is not confined to the specific use and specific embodiment herein described as an illustrative example.

15 Referring to the drawings: there are illustrated views of a coke oven battery or plant of the by-product type, having features above specified, said oven battery embodying in its construction a plurality of crosswise elongated heating walls, 11, 11 and a plurality of intermediate crosswise elongated vertical coking chambers 12, 12, the heating walls 11 forming the side walls of the respective coking chambers 12, as shown in Figs. 2 and 3, and, together with the coking chambers, are supported by the heavy supporting or pillar walls 13, 13 which extend crosswise of the battery and are located, as shown, in Fig. 2, beneath the respective coking chambers 12, 12. These pillar walls, collectively form the main support for the entire superstructure of the oven battery and are themselves supported upon a flat mat or platform which constitutes the subfoundation on which the entire battery rests.

20 The coal to be coked is charged into the several coking chambers or ovens through charging holes 14, located in the top 15 of the battery and positioned directly above the ovens or chambers 12, as shown in Fig. 2. These charging holes 14 are equipped with the usual removable covers, which are removed during charging of the individual ovens or coking chambers and are placed 25 in position to close the tops of such coking chambers during the entire coking or distilling operation. The gases of distillation pass from the tops of the several coking chambers through the usual gas outlets and thence through ascension pipes (not shown) into the usual gas collecting main which carries the distillation products to the by-product recovery apparatus.

30 Heat for coking the charges of coal in the several ovens or chambers 12 is derived from the heating walls 11, which, as above mentioned, extend crosswise of the battery at the sides of the coking chambers. Each heating wall 11 is constituted of a plurality of flame or combustion flues 17. The flame flues of each heating wall are, in accordance with the invention, operatively disposed into a single series, that is to say all of the flues of each heating wall operate concurrently as up-flow or down-flow flues as will be herein-

after more fully explained. The heating walls moreover, are grouped into pairs L of adjacent heating walls, which alternate with intermediate pairs M of such heating walls. When the flame flues of the alternate pairs L are burning, that is to say operating for up-flow, the flame flues of the intermediate pairs M of the heating walls are operating for down-flow, to permit exhaust of the waste gases. 70 75

The crosswise regenerators 18 of the retort oven or battery are located at a lower level than the aforesaid heating walls 11 and coking chambers 12, and, in the present instance, extend in parallelism between the pillar walls 13. Located in the middle lengthwise vertical plane of the battery, is a vertical partition 19, as shown in Fig. 1, which partition extends all the way up from the mat of the battery to the bottom of the overlying heating wall and from one to the other of the pillar walls 13. The regenerators, which are respectively located on opposite sides of the battery extend inwardly to said partition 19 and are separated thereby as clearly shown in Fig. 1. This arrangement permits control from opposite sides of the battery of the flow through the regenerators, thereby assisting the novel flue arrangement in promoting uniformity in distribution. 80 85 90 95

100 Each regenerator 18 is a chamber containing open brickwork, commonly called checker work, and indicated at 20, with a distributing sole channel 21 underneath such checker work, the channels forming the soles of such chambers and opening up into the checker work. The regenerators are heated in alternation by the hot combustion products that draw off from the flame or combustion flues hereinbefore mentioned and then impart such heat to the medium that they feed into these flues. 105

110 In accordance with the invention, the series of regenerators on the opposite sides of the aforesaid central partition 19 are respectively grouped into pairs L' of alternate regenerators corresponding to the pairs L of alternate heating walls, and into pairs M' of intermediate regenerators corresponding to the pairs M of intermediate heating walls. Each regenerator is provided with a series of ducts 23 having forked flow connections 24, all of which lead respectively to individual flame flues 17 of both heating walls of the pair corresponding to such regenerator. With this construction, each flame flue 17 of each heating wall is communicably connected by ducts with both adjacent separate regenerators of its corresponding pair, the flow through the communicably connected regenerators being maintained concurrently in the same direction as the flow through the flues. 115 120 125

130 In the present embodiment of the inven-

tion, the entire series of flame flues 17 of each heating wall 11 is either burning or operating for down-flow to convey waste products to the regenerators beneath and consequently the regenerators aligned on opposite sides of the central longitudinal partition 19 operate concurrently for flow in the same direction and in the same manner. The reversal in flow 10 through the flues 17 on opposite sides of a coking chamber and their communicably connected regenerators may thus be said to take place longitudinally of the battery, instead of transversely thereof as has heretofore 15 been a common practice in this art. The reversal of the oven is effected at the end of an operating period determined by practice and by means of any preferred type of reversing mechanism. The function of such 20 reversal is as follows: The regenerators that prior to the reversal operated as in-flow regenerators become out-flow regenerators, and the out-flow operating regenerators become in-flow operating regenerators. The 25 up-burning series of flues switches function with the down-burning series of flues and the supply of gas is turned off from the previously up-burning flues and turned on into the mains of the previously down-burning flues.

As shown, in Figs. 1 and 2, the series of flues of each heating wall are respectively grouped into pairs N of adjacent flues, and the separating walls 25, which are between 30 the two members of the respective pairs of such flues terminate below the top of the flues, thereby providing out-flow passage-ways 26 for the exhaust of the products of combustion from the flames within the flues. The several 35 separating walls 25, which are constituted of the usual bottle bricks, are provided with a plurality of, in the present instance three, vertical out-flow channels 27, communicably connected at their tops with the respective 40 passage-ways 26, and leading downwardly and respectively opening into cross ducts 28. These cross ducts 28 extend beneath the coking chambers 12 and function to connect the several passage-ways 27 of both members 45 of the pairs of alternate heating walls 11 respectively with the two members of the two intermediate pairs M of heating walls 50 which are located on the opposite side of the said alternate pairs L of heating walls. 55 Thus the entire flow from the heating wall, within the flues of which combustion is being maintained, passes into the passage-ways 26 of the pairs of flues N, thence downwardly through the vertical channels 27 of the 60 bottle bricks, thence, under an adjoining coking chamber through ducts 28 to the vertical channels 27 of an adjacent heating wall, thence up through said channels 27 to the passage-ways 26, and thence downwardly 65 through the out-flow operating flues 17

to the out-flow operating regenerators with which such flues are connected.

The draft through the flues 17 may be regulated by means of the usual movable dampers or sliding bricks 29 located in the 70 passage-ways 26 of the respective flues. These sliding bricks may be reached by access flues 30 which extend from the passage-ways 26 in each heating wall to the top 75 of the battery, there being an access flue positioned over each flame or combustion flue of each heating wall.

Extending crosswise of the battery and located beneath the heating wall 11 thereabove is a pair of gas supply channels 31 and 32. 80 These channels 31 and 32 are for the purpose of supplying coke oven gas to the several flame flues on the opposite sides of the central partition 19, and for this purpose, the channel 31 communicates with the individual flues 17 on one side of said partition 19 by means of ducts 33 that lead from such channel 31 individually into the bottoms of individual flues; and the channel 32 which supplies the several flues that are located on the other side of the before-mentioned partition 19 communicates with said flues by means of similarly connecting ducts. Within the several ducts are disposed the usual nozzles 34. 85 The supply of coke oven gas to the respective channels 31 and 32 is derived from coke oven gas mains of the usual type and respectively located on opposite sides of the battery and extending longitudinally therewith. Suitable means is provided for admitting or cutting off the supply of gas with respect to each pair of channels 31 and 32, it being understood that the gas supply is either concurrently maintained in or concurrently shut off from both channels of a pair. For operating the battery alternatively with use of a special generator gas, such as producer gas, as the fuel, one regenerator of each in-flow operating pair, such as the 90 regenerator P of the pair L', may be optionally connected with a producer gas main, by mechanism such as is disclosed in the before-mentioned application of Joseph Becker, Serial No. 376,126, so that the producer gas may be directed into such of the regenerators P as are operating for in-flow and conveyed through these regenerators into burning flame flues 17.

The operation of the retort oven or battery, when employing a special generator gas, such as ordinary producer gas, as the fuel, is as follows: The supply of coke oven gas to the coke oven gas main and to all of the coke oven gas channels 31, 32, is cut off. 100 A supply of producer gas is permitted to flow into one regenerator P of the in-flow operating pairs, such as the pair L'. Passing through said regenerators, the producer gas is preheated before being delivered into the burning flame flues. During the in-flow 105

- of producer gas into such regenerators P, air flows into the other regenerators A of said in-flow operating pairs L' and passing through said regenerators is preheated prior to its delivery into the burning flame flues, such as the flame flues L of the pairs of alternate heating walls. In the flame flues of the intermediate pairs of heating walls M and in the intermediate pairs of regenerators M' down-flow is maintained, the flame flues of the walls M receiving the waste gases from the before-mentioned channels 27 and cross ducts 28. On reversal of the flow the inflow operating regenerators and flues become out-flow regenerators and flues and concurrently the out-flow regenerators and flues become in-flow regenerators and flues.
- In operating the battery with coke oven gas in the ordinary manner, the supply of producer gas to alternate regenerators P is cut off and air is permitted to flow into such regenerators in place of the producer gas. During coke oven gas operation a supply of coke oven gas is maintained in the channels 31 and 32 which feed the up-burning flues. The reversing mechanism is operated at each reversal to place each of the in-flow operating regenerators in communication with the outer air and concurrently all of the out-flow operating regenerators W in communication with the exhaust. A further mode of operation is with coke oven gas as the fuel combined with a supply of a neutral gaseous diluent to the up-burning flues. In so operating the battery, the supply of producer gas is cut off and the supply of coke oven gas is turned on. Instead, however, of permitting air to flow into regenerators of the series P, waste gas is permitted to flow into such regenerators and be delivered thereby to the up-burning flame flues. The admission into each of the up-burning flues of a supply of neutral gaseous diluent, such as waste gas, is effective to lengthen greatly the flames within such flues and to prevent the localization of the hottest flame temperature in the extreme lower portions of the flues.
- The invention as hereinabove set forth is embodied in a particular form of construction but may be variously embodied within the scope of claims hereinafter made.
- I claim:
1. In a coking retort oven, in combination: a plurality of coking chambers; heating walls contiguous to such coking chambers and respectively constituted of vertical combustion flues disposed into pairs; vertical out-flow channels in each heating wall communicably connected with a pair of combustion flues; duct means extended beneath the coking chambers, said duct means communicably connecting the individual vertical out-flow channels of one heating wall respectively with the

individual vertical out-flow channels of an adjacent heating wall; and cross-wise regenerators parallel with the coking chambers and the heating walls, such regenerators being disposed into in-flow and out-flow operating pairs; each regenerator of each pair being communicably connected with the combustion flues of a pair of adjacent heating walls; substantially as specified. 70

2. In a coking retort oven, in combination: a plurality of coking chambers; heating walls contiguous to such coking chambers and respectively constituted of vertical combustion flues; vertical out-flow channels in each heating wall communicably connected 80 with said combustion flues; duct means extended beneath the coking chambers, said duct means communicably connecting the individual out-flow channels of one heating wall respectively with the individual vertical 85 out-flow channels of an adjacent heating wall; and cross-wise regenerators parallel with the coking chambers and the heating walls, such regenerators being disposed into in-flow and out-flow operating pairs; each regenerator of each pair being communicably connected with the combustion flues of a 90 pair of adjacent heating walls; substantially as specified.

3. In a coking retort oven, in combination: a plurality of coking chambers; heating walls contiguous to such coking chambers, respectively constituted of vertical combustion flues; vertical out-flow channels in each heating wall communicably connected with 100 said combustion flues; duct means extended beneath the coking chambers, said duct means communicably connecting the individual vertical out-flow channels of one heating wall respectively with the individual vertical out-flow channels of an adjacent 105 heating wall; and regenerators communicably connected with said combustion flues; substantially as specified.

4. In combination with the coking chambers of a coke oven battery, heating walls respectively constituting two opposite side walls of the respective coking chambers, said heating walls comprising vertical combustion flues, the flues of the heating walls being 115 communicably connected directly with each other at one of their ends by duct means extended respectively beneath and across the intervening coking chambers, and reversible regenerators connected with said flues at 120 their other ends; substantially as specified.

5. In a coking retort oven, in combination: a series of alternate horizontal coking chambers and heating walls therefor; said heating walls respectively comprising vertical combustion flues; vertical outflow channels communicably connected with said combustion flues; duct means extending beneath the coking chambers, said duct means communicably connecting transversely of the in- 125 130

- tervening coking chambers the vertical out-flow channels of alternate heating walls with the corresponding vertical out-flow channels of intermediate heating walls respectively; and crosswise regenerators communicably connected with the flues of said heating walls; substantially as specified.
6. In a coking retort oven, in combination: a series of alternate coking chambers and heating walls therefor, said heating walls respectively comprising vertical combustion flues; duct means extending beneath the coking chambers and communicably connecting transversely of the intervening coking chambers one of the ends of the flues of the alternate heating walls with one of the ends of the flues of the intermediate heating walls respectively, and regenerators communicably connected with the other of the ends of the flues of said heating walls; substantially as specified.
7. In a coking retort oven, in combination: a series of alternate horizontal coking chambers and heating chambers therefor, said heating chambers respectively comprising vertical combustion flues; said heating chambers being disposed into adjoining pairs by having the combustion flues of a heating chamber communicably connected at one end thereof with the combustion flues of an adjacent heating chamber at one end of the latter flues; and cross-wise regenerators parallel with the coking chambers and the heating chambers, said regenerators being disposed into in-flow pairs and out-flow pairs; the other ends of said combustion flues of adjacent heating chambers of said adjoining pairs of heating chambers communicating with both regenerators of the same pair of regenerators; substantially as specified.
8. In a coking retort oven, in combination: a series of alternate coking chambers and heating walls therefor; said heating walls respectively comprising vertical com-
- busion flues; outflow channels in each heating wall substantially parallel thereto communicably connected with said combustion flues in the same wall therewith; the outflow channels in one heating wall being paired and communicating with the outflow channels respectively in the heating wall on the opposite side of a contiguous coking chamber by a plurality of crossunder ducts crossing under said contiguous coking chamber, said ducts being respectively individual to each of the pairs of paired outflow channels.
9. In a coke oven battery, in combination: a series of alternate coking chambers and heating walls therefor, each of said heating walls comprising vertical combustion flues, a plurality of duct means in each of said heating walls, the flues of each heating wall being disposed into pairs each of which pairs is individual to and communicates with one of said duct means in the same wall therewith and at the upper ends of the flues, each of said duct means in one heating wall being individual to and communicating with one of said duct means in another heating wall by duct means passing beneath an intervening coking chamber; and reversible regenerators respectively connected with the other ends of the pairs of flues.
10. In a coke oven battery, in combination: a series of alternate coking chambers and heating walls therefor, each of said heating walls comprising vertical combustion flues, the upper ends of the flues in one of said heating walls being communicably connected with the upper ends of the flues in another of said heating walls by duct means passing beneath an intervening coking chamber; and reversible regenerators connected with the other ends of said flues.

In testimony whereof I affix my signature this 26th day of August, 1921.

NATHANIEL G. PARRY.
